UNITED STATES PATENT OFFICE.

THOMAS J. PRICE, OF DANVILLE, KENTUCKY.

HEMP-BRAKE.

1,280,085.

Specification of Letters Patent. Patented Sept. 24, 1918.

Application filed February 3, 1917. Serial No. 146,416.

To all whom it may concern:—Be it known that I, THOMAS J. PRICE, a citizen of the United States of America, residing at Danville, in the county of Boyle and State of Kentucky, have invented certain new and useful Improvements in Hemp-Brakes, of which the following is a specification:

My invention relates to an improvement 10 in hemp-brakes, and pertains more particularly to such a device in which a resilient cushion-block is provided to receive the impact of the crushing-block. The object of my invention is to provide means for varying the tension upon the resilient cushion-block, as desired. A further object is the provision of a blower in position to actuate the hemp just as it is broken between the crushers. Further objects will become apparent as the explanation proceeds.

In the accompanying drawings:—

Figure 1 is a top plan view of my improved hemp-brake;

Fig. 2 is a vertical section taken on the 25 line 2—2 of Fig. 1;

Fig. 3 is a vertical cross-section on the line 3—3 of Fig. 1; and

Fig. 4 is a fragmentary perspective view of one end of the hemp-brake.

A frame 1 of any desired construction is provided at the ends with flanged upright braces 2, 2, which have connected to their upper ends the slide-ways 3, 3. Slidably mounted in the slide-ways 3, 3, is the crushing-block 4 of any required design, which has pivotally mounted at its rear at 5, 5, the pitman-rods 6, 6. The other ends of the pitman-rods 6, 6, are pivotally connected with the crank shaft, 7, extending through 40 the slide-ways 3, 3. The crank-shaft 7 is provided with the usual fly-wheel 8 and drive-pulley 9.

In one end of the slide-ways 3, 3, is slidably positioned the cushion-block 10, the 45 face of which may be of any required design to coöperate with the face of the crushing-block 4. The cushion-block 10 is rigidly fixed to a back-plate 11, which has laterally-extending ears 12, 12, extending beyond the 50 line of the slide-ways 3, 3. In the upper ends of the upright flanged braces 2, 2, are openings 13, 13, which are in line with each opening 14, 14, in the laterally-extending ears 12 of the back-plate 11.

55 Retaining-rods 15, 15, extend through

openings 13, 13, and 14. Any desired form of adjustable stop, such as a nut 16, may be provided at the end of the rod 15 passing through the ears 12. At the other end of the rod 15, a helical spring 17 is positioned about the rod, and engages the vertical flanged brace 2, at one end, and a suitable adjustable stop 18 at the other.

It will be obvious that by the means just described a greater or less tension can be put on the ears 12, and thence on the back-plate 11, which tension governs the amount of resiliency which the cushion-block will have. It will further be apparent that with this form of construction it will be practically impossible to choke the machine, inasmuch as it will be impossible to get too much of the hemp between the blocks, as the cushion-block will always be capable of yielding the required amount.

75 In any desired position on the frame 1 is located a blower 19, which is actuated by the customary pulley 20, and has an opening directly beneath the blocks 4 and 10, so that the hemp, as it is crushed, may drop by 80 gravity down into the blower, from which it may pass at the opening 21.

In order to prevent the air from blowing up out of the opening beneath the blocks 4 and 10, when they are in their engaged position, I provide a cover-plate 22, which is fastened to the bottom of the block 4, and adapted to travel therewith in the slide-ways 3.

It is obvious that many slight changes 90 might be made in my construction without departing from the spirit of my invention; hence I do not wish to be limited to the precise structure set forth, but:—

I claim:

1. In a hemp-brake, the combination with upright braces having slide-ways connected with their upper ends and provided with openings, and a frame supported by the braces, of a cushion-block guided by the slide-ways, rods connected with the cushion-block and extending slidably through the openings in the upright braces, springs connected with the rods, tension means for regulating the tension of the springs, a reciprocating crushing-block operating between the slide-ways and coöperating with the cushion-block, and means actuating said reciprocating crushing-block.

2. In a hemp-brake, the combination with

- upright braces having slide-ways connected with their upper ends and provided with openings, and a frame supported by the braces, of a cushion-block guided by the 5 slide-ways, rods connected with the cushion-block and extending slidably through the openings in the upright braces, springs connected with the rods, tension means for regulating the tension of the springs, a reciprocating crushing-block operating between the slide-ways and co-operating with the cushion-block, an outlet opening immediately beneath the space between cushion and crushing-blocks for the discharge of the 10 hemp; a blower for forcing air into said outlet, and means for driving said blower and crushing-block reciprocating means.
3. The combination with a frame, of a blower, a crushing-block mounted on the 15 frame in proximity to said blower, a cover-plate carried by said crushing-block and adapted to close the opening to the blower when said block is in one position, a cushion-block mounted on said frame, resilient detaining means connecting said cushion- 20 block with said frame, and means for actuating said crushing-block.
4. In a hemp-brake, the combination with a frame, of a crushing-block mounted thereon, a cushion-block mounted on said frame, 25 a back-plate on said cushion-block having openings and extending laterally therefrom, rods extending through the openings in said frame and said back-plate, adjustable means on one end of each rod, resilient means on 30 said rods between the frame and said adjustable stops, and adjustable stops on the other end of each rod adapted to bear against said back-plate, whereby said cushion-block is yieldingly held in position. 35
5. In a hemp-brake, the combination with a frame, of a slide-way therein, a reciprocating crusher-block mounted in the slide-way, a cushion-block resiliently mounted in said slide-way in position to be engaged by 40 said crusher-block, and means for reciprocating said crusher-block.

In testimony whereof I affix my signature.

THOMAS J. PRICE.
